UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed February 8, 1924. Serial No. 691,335.

This invention relates to feed-roll-releasing mechanism in typewriting machines, and is particularly useful in facilitating placing and fixing of bills in typing position, especially where a record-sheet is employed upon which to make carbon copies or entries of successive bills.

According to the invention, from the front of the platen and from any desired position along the platen, the operator may release the feed-rolls that run on the under side of the platen, and may also make said releasing operation constitute a part of the sheet-collating operation. The device includes a sheet-aligning bar or collating table extending along the platen, and hinged so as to be swung forwardly to cast off the feed-rolls, and may be locked forward. Said aligning bar or collating table may be held in an intermediate position during the insertion of the work-sheet.

The work-sheet may be positioned for typing by means of the upper edge of the aligning bar, assisted by the fingers of the typist, or a ledge at the upper edge of said bar. To accommodate various lengths of bills, the ledge may be adjustably mounted on the bar, to act as a gage.

The aligning bar may be readily adjustable lengthwise of the platen.

Other features and advantages will hereinafter appear.

In the accompanying drawings,

Figure 1 is an end elevation, partly in section, of the carriage and associated parts of a typewriting machine embodying the present invention, and showing the feed-rolls in effective position.

Figure 2 is similar to Figure 1, but shows the feed-rolls released during the insertion of a bill.

Figure 3 is a front elevation of the carriage, showing the feed-roll-releasing means and other parts.

Figure 4 is a fragmentary side elevation, partly in cross-section, showing an adjustable ledge mounted on the aligning bar.

Figure 5 is a diagrammatic front elevation of the device shown in Figure 4.

A platen 10 by means of an axle 11 is journaled in side plates 12 of a platen-frame, shiftable up and down by the case-shifting mechanism, including guide-link 9, usual in a standard Underwood typewriting machine. The usual rear paper shelf 13 has an

apron extension 14 for guiding work-pieces down behind the platen 10 and around under the same to the printing line at the front thereof. Front feed-rolls 15 are on a shaft 17 seated on arms 18 of bell-crank levers 60 pivotally mounted on a shaft 19. Rear feed-rolls 16 are on a shaft 20 seated on arms 21 of bell-crank levers also pivotally mounted on shaft 19. The bell-crank levers which comprise the arms 18 have other arms 22 65 which depend to the rear of a shaft 24, and the bell-crank levers which comprise the arms 21 have other arms 23 which depend to the front of the shaft 24. Leaf-springs 25 bearing against arms 18 and 21 tend to 70 rock the arms upwardly to throw the feed-rolls 15 and 16 against the platen 10, and, therefore, tend to press the arms 22 and 23 against the shaft 24. Shaft 24 has flats 26 cut thereon where the arms 22 and 23 engage the same. When the feed-rolls 15 and 16 are in effective position, the arms 22 and 23 stand slightly free of the flats 26, as shown in Figure 1. When, however, the shaft 24 is rotated, the arms 22 and 23 are 80 forced apart to draw down the feed-rolls 15 and 16, as shown in Figure 2. The shaft 24 is journaled in the hanger-plates 31 supported from shaft 19. The feed-roll mechanism, just described, is that found on the standard Underwood typewriting machine.

The feed-rolls 15 and 16 may be thrown off the platen 10 by means of a release-control-device 32 besides the usual release-control lever-key 33 through the following interconnecting parts. Fast to the shaft 24 is an arm 34 which is connected at one end to a link 35, which is connected to a crank-lever 36 having a rigid stub-shaft 37, mounted between the right-hand side plate 12 of the platen-frame and a side bracket 38^a, and mounted on the outer end of the stub-shaft 37 is the lever-key 33 as shown in Figure 3. The release-control-device 32 may comprise the rod 38 extending over the platen 10 and running lengthwise thereof. Rod 38 is fastened at each end to supporting arms 39, the free ends of which are pivoted at 39^a on downwardly-extending members 40 mounted on and extending from the front top-portion of the platen-frame side pieces 12. An aligning bar 41 which is in effect a collating table also serves as a handle for the control-device 32 and may be mounted to move with the rod 38 by means of widely 105 110

spaced bracket-arms 42 fastened to the bar 41 and slidingly embracing the rod 38. Rod 38 may be provided with a flattened surface 43 extending lengthwise thereof, and each bracket-arm 42 may have a finger-screw 44 threaded therein to bear on the flattened surface 43 of the rod 38 for adjusting the bar or collating table 41 along the rod 38 and to prevent the turning of the bar on the rod. A side-gage 45, adjustable for limited movement, may be mounted on the left-hand end of the bar 41 for positioning a work-sheet 46 during the front insertion thereof.

15 To interconnect the release-control-device 32 with the feed-roll-releasing mechanism, a short arm 47 is rigidly fastened to the inwardly-extending end of the stub-shaft 37, and may have an open-ended slot 48 extending down from the free end thereof, in which may rock a co-operating pin 49 secured in the right-hand swingable supporting arm 39.

In the drawings, a record-sheet 50 faced by a carbon-sheet 51, is shown as having been fed down the table 13 and around the platen 10, and as having a typed portion thereof extending rearward over the top of the platen 10. The record-sheet 50 receives the entries made successively upon a series of individual short sheets or cards, bills or statement-sheets 46, and, in order that the record-sheet 50 may be held in place upon the platen 10, while the feed-rolls 15 and 16 are released for inserting or removing bill-sheets 46, usual downwardly-extending fingers or clips, carrying rolls supported above the platen 10, may be provided. These fingers are not shown but the rolls are indicated in the dotted lines at 52.

In typing on well-known work-piece forms comprising a card, statement or bill sheet 46, which is to be inserted from the front of the machine against a record-sheet 50 on the platen 10, the record-sheet 50 and the carbon 51 are first fed around the platen 10 to typing position, while the feed-rolls 15 and 16 are in effective position, by means of the hand-wheels 53 on platen-axle 11, or by the usual line-spacing mechanism, including the line-space wheel 53a. The paper-finger rolls 52, if not previously applied, are then applied to the record-sheet 50 and the carbon 51, as indicated in Figure 1. The typist then draws the bar 41 forwardly and passes a statement-sheet 46 in front of the carbon-sheet 51 on the platen 10. As the bar 41 is thus actuated, it causes the pin 49 on the supporting arm 39 to rock arm 47, which, in turn, operates the feed-roll-releasing mechanism, to throw the feed-rolls 15 and 16 off the platen 10, permitting the insertion of the lower edge of the bill-sheet 46 around the platen 10 between the latter and the apron 14 (see Figure 2). The

bill-sheet 46 may be accurately positioned for typing by means of side-gage 45 and by using the upper edge of the aligning bar 41, assisted by the fingers of the typist, as shown in Figure 2. Bar 41 may then be restored to its initial position, permitting springs 25 to throw feed-rolls 15 and 16 toward the platen 10, for holding the bill-sheet 46.

Figure 2 shows the aligning bar 41 in its extreme forwardly-moved position for readily locking the feed-rolls 15 and 16 away from the platen 10, but it is obvious that the bar 41 may be moved to an intermediate position, in which case, upon the removal of the finger of the typist from the bar 41, the control-device parts will automatically be restored to their normal effective position. After the typing of a bill-sheet 46 is completed, the carriage is thrown rightward for commencement of writing on another statement-sheet. The lever (not shown), by which the carriage is thus returned, ordinarily effects a single line-space movement of the platen 10 by a mechanism not here shown. This results in a line-space movement of the record-sheet 50 and the carbon 51, so as to prepare the same for receiving the entry to be made on the next succeeding bill-sheet 46. The bill-sheet 46 in the machine may be removed after the bar 41 is drawn forward and another inserted as described above.

Instead of positioning the bill-sheet 46, for typing, on the aligning bar 41, assisted by the fingers of the typist, an adjustable ledge or gage 57 may be mounted on the bar for accommodating various lengths of bill-sheets and for aiding the bar 41 to position the bill-sheet 46. The gage 57 may be formed of a forwardly-extending shoulder-piece 58 forming a gage for the upper edge of the bill-sheet 46, and downwardly bent from said shoulder 58 may be spaced arms 54 adjustably mounted on the bar 41 by means of thumb-screws 55 passing through slots 56 in the arms 54 and threaded into the bar 41, as shown in Figures 4 and 5.

It will be understood that the record-sheet and the carbon-sheet may be adjusted around the platen while the feed-rolls are released, and that these sheets may be held in position by the rolls 52 of the paper-fingers. It will further be understood that the first bill-sheet 46 may be inserted around the platen from the back, and then adjusted, as above described, to the printing point, after which the feed-rolls may be thrown on to hold all of the sheets on the platen. The succeeding bill-sheets 46 may each be inserted from the front of the platen after the feed-rolls have been released, and prior to the removal of the preceding bill-sheet, the latter serving as a means to guide the fresh or untyped bill-sheet around the platen.

Pivots 39^a are preferably arranged in alignment with the position of the printing line on platen 10, so that the distance from the printing line to the upper edge of the bar 41 is always the same, thus avoiding any possibility of shifting the printing line on the bill-sheet 46 with respect to the position of the printing line on platen 10 when swinging the bill-sheet 46 with the bar 41 from the position shown in Figure 2 to that shown in Figure 1.

The above description explains the operation of a typewriting machine embodying the invention for typing a relatively complex work-piece. It is obvious that simple and ordinary forms may be typed with equal advantage by the use of the same.

The bill-sheet may be held, or, in other words, may be prevented from unnecessarily falling forward, by a finger 60, which may be supported on the usual front bar (not shown) of the carriage-frame. The finger may be so supported that it may be conveniently swung out of the way while inserting a fresh bill.

Variations may be resorted to within the scope of the invention, and portions of the improvements may be used without others.

Having thus described my invention, I claim:

1. In a typewriting machine, a platen-carriage, a platen mounted for case-shifting thereon, a releasable work-piece-feeding mechanism co-operating with the platen, and control means for said mechanism shiftable with the platen, comprising a rod operatively connected to said mechanism, the rod being supported on the carriage and extending lengthwise of the platen, and a bar adjustably mounted along the rod for actuating the latter.

2. In a typewriting machine, a platen-carriage, a platen, means for shifting the platen between case-positions on the carriage, a releasable work-piece-feeding mechanism co-operating with the platen, control means shiftable with the platen and extending lengthwise thereof, said control means including a rod, a bar slidably mounted for movement on the rod to release said mechanism during the removing or inserting movement of a work-piece in the machine, and a gage-plate adjustably secured to the bar for aligning work-pieces of various lengths in typing position.

3. In a typewriting machine, a platen-carriage, a platen, feed-rolls to co-operate with the platen, and a device pivotally mounted on the carriage lengthwise of the platen, comprising control means for releasing the feed-rolls and gaging means for positioning a work-piece for typing, said device being arranged to pivot about points aligned with the printing line of the platen, so that the distance between said gaging means and the

printing line is always the same as the device is moved with the work-piece.

4. In a typewriting machine, a platen-carriage, a platen, feed-rolls to co-operate with the platen, and a device comprising a rod movably mounted on the carriage lengthwise of the platen, a bar supported on the rod for movement therewith to release the feed-rolls, and an aligning edge on the bar to position, for typing, a work-sheet being inserted in the machine, said device when actuated being pivoted to swing about the printing line on the platen, so that the distance between said aligning edge and the printing line is always the same as the device is moved with the work-sheet.

5. In a typewriting machine, a platen-carriage, a platen, feed-rolls to co-operate with the platen, and a device comprising a rod movably mounted on the carriage lengthwise of the platen, a bar supported on the rod for movement therewith to release the feed-rolls, and a gage-plate adjustably secured to the bar for aligning work-sheets of various lengths in typing position, said device when actuated being pivoted to swing about the printing line on the platen, so that the distance between said gage-plate and said printing line is always the same as the device is moved with the work-sheets.

6. In a typewriting machine, a platen-carriage, a platen, feed-rolls to co-operate with the platen, and a device to be actuated by the hand of the operator, comprising a rod swingably supported on the carriage lengthwise of the platen, and a collating table mounted on the rod and operable to swing said rod whereby to release the feed-rolls, said table having an aligning edge thereon for gaging a work-sheet to position for typing.

7. In a typewriting machine, a platen-carriage, a platen, feed-rolls to co-operate with the platen, a device to be actuated by the hand of the operator, comprising a rod swingably supported on the carriage, a collating table mounted on the rod and operable to swing said rod whereby to release the feed-rolls, and a gage-plate adjustably secured to the bar for aligning work-sheets of various lengths in typing position, said gage-plate including a ledge against which the work-sheets are positioned for gaging.

8. In a typewriting machine, the combination with a platen, of means to feed a work-sheet around said platen, and collating table operatively connected to means and movable to release or restore the same.

9. In a typewriting machine, a platen, a releasable pressure-device for holding a work-piece against the platen, and a work-collating table connected to said pressure device and directly movable to release or restore the same.

10. In a typewriting machine, a platen, a

4
releasable pressure-device for holding a work-piece against the platen, and a work-collating table connected to the pressure-device, said table being movable from one position to another position, independently of the platen, and effective by such movement to release said pressure-device.

11. In a typewriting machine, a platen, a releasable pressure-device for holding a work-piece against the platen, and a collating table connected to the pressure-device and swingable forwardly and rearwardly adjacent the front of the platen, but independently thereof, said table when swung forwardly being effective to release the pressure-device, and when swung rearwardly effective to restore said pressure-device.

12. The combination with a typewriting machine having a platen, a pressure-device for holding a work-piece against the platen, and releasing mechanism for the pressure-device including an operating lever, of a collating table movably mounted adjacent the front of the platen, and movable independently of the platen, and connections between the table and said operating lever whereby such independent movement of said table in one direction releases the pressure-device, and movement of said table in the opposite direction restores said pressure-device.

13. The combination with a typewriting machine having a platen, a pressure-device

for holding a work-piece against the platen, and releasing mechanism for the pressure-device including an operating lever, of a collating table including a pivotally-mounted arm arranged to swing forwardly and rearwardly adjacent the front of the platen, and a pin-and-slot connection between said arm and the operating lever, so that when the table is swung forwardly the pressure-device is thereby released, and when said table is swung rearwardly said pressure-device is restored.

14. In a typewriting machine, a platen, a collating table, a releasable pressure-device for holding a work-piece against the platen, and operating connections between the pressure-device and the collating table, the latter being swingable forwardly adjacent the front of the platen to release the pressure-device and to bring the work-gaging surface of said table tangential to the front of the platen and substantially vertical thereover, whereby a work-piece may be inserted in the machine straight downwardly at the front of the platen, the lower portion of said work-piece being inserted between the bite of the pressure-device and the platen, and the upper edge of the work-piece gaged on the collating table prior to swinging said table rearwardly to restore said pressure-device.

JOHN WALDHEIM.
